WITNESSES:

UNITED STATES PATENT OFFICE.

BRYANT HARRIS AND WILLIE VAN BUREN, OF HELENA, ARKANSAS.

HORSESHOE.

1,401,074.

Specification of Letters Patent. Patented Dec. 20, 1921.

Application filed July 6, 1920. Serial No. 394,392.

To all whom it may concern:

Be it known that we, BRYANT HARRIS and WILLIE VAN BUREN, citizens of the United States, residing at Helena, in the county of 5 Phillips and State of Arkansas, have invented new and useful Improvements in Horseshoes, of which the following is a specification.

The object of our present invention is the 10 provision of an improved and practical horseshoe of the type that is adapted to be affixed to a horse's hoof without the employment of extraneous devices.

To the attainment of the foregoing the invention consists in an improvement as hereinafter described and definitely claimed.

In the accompanying drawings, hereby made a part hereof:—

Figure 1 is a top plan view of our novel 20 horseshoe;

Fig. 2 is a side elevation of the same;

Fig. 3 is a transverse section taken in the plane indicated by the line 3—3 of Fig. 1 and showing the adjustable means for fitting 25 the shoe to a hoof; and

Fig. 4 is an enlarged detail view illustrative of the manner in which the toe clip is connected with the major members of the shoe.

Similar numerals of reference designate 30 the corresponding parts in all of the views of the drawings.

Among other elements our novel shoe comprises two curvilinear major members 1 which are preferably provided at their heel 35 ends with calks 2. Each of the said members 1 is provided at intervals in its length with outwardly extending clips 3, designed to rest at the side of a hoof when the shoe 40 is applied thereto. The said members 1 are connected at their forward ends in hinged manner, as indicated by 4. Carried by the hinge pin 4 is a calk 5.

Interposed between the major members 1 45 at an intermediate point in the lengths thereof is a transverse, telescopic tubular casing 6.

Extending through the casing 6 and 50 adapted to be turned about its axis therein is a transverse bolt 7 having oppositely threaded portions 8, in engagement with correspondingly threaded sockets in the members 1, whereby when the bolt 7 is turned in one direction the members 1 will 55 be drawn toward each other, and when the

bolt 7 is turned in the opposite direction the members 1 will be thrust apart. By virtue of the said provision the shoe manifestly may be quickly and nicely adjusted to hoofs of different sizes. It will also be noted that 60 because of the disposition of the bolt 7 in the telescopic casing 6 the bolt is at all times protected against moisture and dirt. One end of the bolt 7 is provided with an angular end 8^a, and one of the shoe members 65 1 is provided with a lateral tubular projection 9. The said tubular projection 9 is adapted for the insertion of the shank of a removable key 10 which is employed to turn the bolt 7 about its axis and adjust the shoe, 70 and is then disassociated from the shoe.

It will be apparent from the foregoing that when the capacity of adjustment of our novel shoe and the facility with which the same may be securely fastened on a horse's 75 hoof are taken into consideration, the shoe is simple and inexpensive and does not embody any delicate members such as are likely to get out of order after a short period of use.

Having described our invention, what we 80 claim and desire to secure by Letters-Patent is:—

1. A horseshoe comprising two hingedly connected major members in which are oppositely-threaded transverse-aligned apertures, telescoped tubular casing sections carried by and arranged between the major members, and a transverse bolt extending through said casing sections and having oppositely-threaded portions in engagement 85 with the threaded apertures of the major members and adapted at one end for the application of a turning implement.

2. A horseshoe comprising two hingedly connected major members, a transverse telescopic tubular casing interposed between intermediate parts of said members, and a transverse bolt arranged in said casing and having threaded portions in engagement 95 with correspondingly threaded sockets in the major members, one of the major members being provided with an exterior lateral tubular projection for the insertion of a removable key, and one end of the bolt being of angular formation for the engagement 100 of said key.

In testimony whereof we affix our signatures.

BRYANT HARRIS.
WILLIE VAN BUREN.
